US0D1023110S

(12) **United States Design Patent** (10) Patent No.: **US D1,023,110 S**
(45) Date of Patent: ** Apr. 16, 2024

(54) **LENS COVER**

(71) Applicant: **Matrixed Reality Technology Co., Ltd.**, Wuxi (CN)

(72) Inventors: **Yuanyuan Wu**, Beijing (CN); **Yafeng Zhou**, Beijing (CN); **Jun Wang**, Beijing (CN)

(73) Assignee: **Matrixed Reality Technology Co., Ltd.**, Wuxi (CN)

(**) Term: **15 Years**

(21) Appl. No.: **29/830,177**

(22) Filed: **Mar. 10, 2022**

(30) **Foreign Application Priority Data**

Sep. 29, 2021 (CN) 202130648603.3

(51) **LOC (14) Cl.** **16-06**

(52) **U.S. Cl.**

USPC **D16/101**

(58) **Field of Classification Search**

USPC D14/372; D16/100, 101, 300-342; D29/105-110
